(57) **CLAIM**

The ornamental design for a cup shaped video player game as shown and described.

DESCRIPTION

FIG. 1 is a top front right isometric view showing the cup shaped video player game of the invention.

FIG. 2 is a bottom rear left isometric view showing the cup shaped video player game of FIG. 1.

FIG. 3 is a front view showing the cup shaped video player game of FIG. 1.

FIG. 4 is a rear view showing the cup shaped video player game of FIG. 1.

FIG. 5 is a right side view showing the cup shaped video player game of FIG. 1.

FIG. 6 is a left side view showing the cup shaped video player game of FIG. 1.

FIG. 7 is top view showing the cup shaped video player game of FIG. 1; and,

FIG. 8 is bottom view showing the cup shaped video player game of FIG. 1.
